S. H. GILMAN.

Evaporating Pan.

No. 15,421.

Patented July 29, 1856.

UNITED STATES PATENT OFFICE.

SAML. H. GILMAN, OF NEW ORLEANS, LOUISIANA.

IMPROVEMENT IN SUGAR-EVAPORATORS.

Specification forming part of Letters Patent No. 15,421, dated July 29, 1856.

To all whom it may concern:

Be it known that I, SAMUEL H. GILMAN, of New Orleans, Louisiana, have invented a new and useful Circulating Sugar-Boiler, resembling and yet essentially differing from the ordinary train of open kettles; and I do hereby declare the following to be a full, clear, and exact description of the same, reference being had to the annexed drawings, made part of this specification, and lettered to correspond therewith.

For the reasons that four-fifths of the sugar is manufactured in a train of open kettles, varying in diameter from eighty-four inches for the "grande" down to forty-two inches for the "battery;" that the plantation negroes cannot handle to advantage the complex arrangements of open kettles boiled by direct heat, or of steam-evaporators, as hitherto devised; that the mechanism, structure, and manipulation of such plans are open to serious objections, and that from various causes—such as leakage in the "tiling" of the ordinary train of open kettles, brushing from one kettle into another from the battery to the grande, delays in passing up from the grande to the battery, the impossibility of assimilating the condition of any larger quantity than any one kettle of the old-fashioned train will hold, the dependence of the cleanliness of the juice to be "passed up" resting entirely upon the care given by the attendant, the uncertainty of the condition of things even under the best management, and when steam is used the liability to derangement in some of the necessarily complex arrangements when plantation hands only can be or are employed—I have made it the object of my invention to produce a plan for a circulating sugar-boiler which is simple enough to be worked by plantation negroes, is readily adapted to any sized plantation, and is free from the most serious defects hitherto developed in the practical use of all plans not too philosophical nor too futile to be tried. This plan will economize fuel, increase evaporating-surface, come within the means (as to cost) of any sized plantation, pass up the juice in great quantity hydrostatically, and, most important of all, cleanly, will brush the scum of each kettle into an appropriate place, will receive all overflow in the same manner, will be proof

against all leakage, unless almost direct efforts are used to make it leak, and will be easy of access for cleansing or other purposes.

The nature of my invention consists in a train of open kettles of any suitable size or number, set lengthwise centrally in a long kettle, which is thus divided into two side kettles, (in regard to the train,) and which, by a channel-way or juice-space that leads from one to the other of these divisions, underlies the train and forms the sides and bottom of the flue, passing direct from the furnace under the train of kettles, and by the side kettles (into which the insertion of the train of central kettles divides it) and the vertical portion of the juice-space forms the top and one side of each return-flue; and, again, by the lower side of the juice-channel above mentioned forms the top of the flue leading to the chimney, the long kettle communicating by a pipe (which rises up from the farthest division of the channel-ways and through the main flue formed by the train and the long kettle) with the central kettle next to the battery, thus filling this kettle hydrostatically from a large body of assimilated juice; and, furthermore, brushing the grandes and first kettle and catching their overflow in one set of troughs and providing similarly for the remainder of the kettles by another set of troughs, so that each kettle is separated from the adjacent one and operated in and by itself.

The construction of my plan is as follows:

Fig. 1 is a top view. Fig. 2 is a longitudinal vertical and central section. Fig. 3 is an end elevation. Fig. 4 is a vertical cross-section at the line P Q, the brick-work being shown, so as to define the return side-flues, E and D; and the bottom discharging-flues, K.

A is the flue leading direct from the furnace. The top of this flue is formed by the train of kettles L M N O R, and the sides and bottom of this flue are formed by that portion of the long kettle B C which, thus underlying the flue, enables the part B to communicate with the part C, and B C as one kettle to communicate with the kettle O of the train by means of the vertical pipe S, which rises up from this underlying part for this purpose. Suitable brick-work or masonry connects the flue A with the return-flues D and

E, which pass, respectively, under the portions B and C of the long pan. It will thus be perceived that the flue A during its entire passage through the length of the kettles is surrounded by the fluid to be boiled. The evaporating side kettles, B and C, are as wide as the return-flues D and E, so that the heat from these flues is made fully effective upon the bottoms of these side kettles. Suitable brick-work or masonry connects these return-flues D and E with the flue K, which passes beneath the bottom of the portion of the kettle B C that underlies the flue A. The flue K passes off the results of combustion to the usual stack or chimney. It will be observed also that the vertical portions of the juice-space or channel-way of the kettle B C form one side each of the return-flues D and E, Fig. 4. It will be seen, therefore, that all the effective heat is applied to the largest surface which can be made available in the construction of a train of kettles set in a flue-surrounding and flue-covering kettle.

The dotted lines T U V and the dotted arrows W X Y (seen in plan in Fig. 1) show the channels made from end to end of the flue-underlying part of the kettle B C by the partitions T U V, so that the fluid poured into B has to pass around by the arrow W, and then back again, and round by the arrow X, before the fluid can rise up in the side portion C of the long kettle B C, and the fluid has to pass round by the arrow Y before it can have access to and rise up in the pipe S to the central kettle O at the battery end of the train. The partition U is put in contact with the pipe S. The partition V is also in contact with the pipe S. Thus as the pipe S rises up to the bottom of the central kettle O, next to the battery R, the fluid must all pass with this channel up the pipe and into the kettle O, whence it is bailed out into the battery. Two troughs, F and G, run alongside each portion B and C of the long kettle B C. Transverse troughs run athwart the train of central kettles and the long kettle in this wise. A transverse trough, J, divided into two parts transversely to itself at *a*, and discharging itself, as shown by the arrows, allows the central kettle O and the battery R to overflow or have any scum or floating impurity brushed thereinto and pass off into the trough G, running alongside the part C of the long kettle. A transverse trough, I, divided into two parts transversely to itself at *b*, and discharging itself, as shown by the arrows, allows the central (grandes) kettle M and N to overflow or have any scum or floating impurity brushed thereinto, and pass off into the trough F, running alongside the part B of the long kettle. A transverse trough, H, divided into two parts transversely to itself at *c*, and discharging itself, as shown by the arrows, allows the central (grandes) kettle L to overflow or have any scum or floating impurity brushed thereinto and pass off into the trough F. The por-

tion B of the long kettle overflows, or is cleansed by brushing any scum or impurity floating therein into the portions of the transverse troughs J, running athwart it near the battery end I about midway, and H at its grande end. The same arrangement at the other end of the transverse troughs, above mentioned, appertains to the portion C of the long kettle, with the exception that the troughs for B discharge into the long trough F, and those for C into the long trough G. The sides of the transverse troughs J and I and the kettle side of the transverse trough H form the lower sides of the train of central kettles. The outer sides of the troughs F and G are higher than the central kettles, and the train of central kettles higher (except the transverse trough side) than the long kettle. The central kettles are all at one level on their highest sides, and the long kettle is of the level of the transverse troughs, I and J of which pierce the sides of the train or, what is the same, have an issue therethrough, except at *a* and *b*, as above mentioned. The bottoms of the train of central kettles are cylindrical lengthwise the train.

The "grandes" L M N, as they may be termed, are oblong in the same line. The receiving-kettle O is nearly square, and the battery R oblong crosswise the train. These proportions are not a necessity, and therefore are not noted in definite measures. Suffice it to say that the longest kettles ordinarily cast or made are from six to seven feet in diameter for the grande, and the size is reduced till the smallest battery size is retained.

In my train of kettles it will be observed that I expose the ends of the train of central kettles to the heat by making the lower portions, or so much as constitutes the cylindrical portion, shorter than the portions above the level of the flat bottoms of the long side kettles, B and C. It will be seen also that the cylindrical part of L M N are of equal depth to each other, and are deeper than O, and O than R. Figs. 2 and 3 show this. It must be obvious that with a very slight increase in area required for the ordinary open train I attain a greatly increased flue-heating and evaporating surface. The largest train of six kettles, as they are now used, presents an amount of heating-surface to the fire and flues of two hundred and fifty-four square feet, and requires one and one-half cord of wood per hour, which is equal to one cord of wood per hour for every one hundred and sixty-three square feet. The proportion of wood per hour to heating-surface in the best class of steam-evaporated sugar-boilers is one cord to one thousand square feet of heating-surface. This sugar-boiler, as described, will have a proportion of eight hundred to twelve hundred square feet of heating-surface to each cord of wood per hour. This heat is directly applied, and of course not liable to the drawbacks of transfer of heat, loss by condensation, leakage, &c., in transmitting the steam

from the steam-making boilers to the sugar-boilers.

Over the ordinary open train of semi-spherical sugar-kettles this circulating sugar-boiling arrangement, as described, has this advantage—

First. Absolute protection against loss from boiling over. The rows of globular-formed open kettles are set in masonry by resting their flanges on a circular brick wall, which is the top of the furnace-wall beneath the kettles. A brick wall, termed "tiling," flares outward and upward to the height of a foot or so above the iron flange, so that the diameter of the top of the tiling is considerably greater than the diameter of the top of the kettle. This tiling always crack and leaks more or less of the juice through into the fire, and the quantity thus lost can never be known and is seldom discovered until the fire is quenched thereby.

Second. Facilities by means of the arrangement of the troughs for brushing off the scum or other floating impurities into troughs along and level with the adjacent sides of the kettles in such wise that the scum or floating impurity is never passed from one to another kettle, but is passed to other troughs or settling-reservoirs, from which the juice can be collected with the least possible loss of temperature, &c.

Third. Passing up in large quantity, by means of the long kettle, that portion of the juice in condition to be thrown into the battery, it being a well-known general law that fluids holding in solution substances to be extracted therefrom work best and give the most even and equitable result as well in regard to quantity as quality when the fluids are in large bodies.

Fourth. Passing up the same circuitously, and after the first ladling into the side portion B hydrostatically, from the less to the more heated—that is, from the grande to the battery-end of the kettle B C, and thus securing the cleanliness of the juice against any oversight or neglect of the hands in attendance, because the scum and impurities being of less and less specific gravity in comparison to the saccharine juice (owing to the increasing density of the juice) and the currents due to the boiling process being from the battery to the grande end of the kettle B C, and ladling being done at and toward that end of B, the scum and impurities must rise and float toward the grande end of the kettle B C, and the purest juice alone reaches the vertical pipe S, rising up as it does from the most distant part of the channel from the grande end and the nearest part of the flue-underlying channel to the kettle O at the battery end, thus beneficially bringing physical law into simple and effective operation, and in a manner always to benefit and never to detract from the personal attention bestowed upon the sugar-making process. It will be observed that the scum and light impurities have

the entire length of the side portions, B and C, to rise up to the surface, and thus every possible facility for floating from the battery end of the kettle B C, physical law, mechanical arrangement, and personal attention all combining to produce that result. I thus attain the most important feature in the process of sugar-making—viz., bringing the juice clean and pure to the battery end, and so that no fears of cooking need be entertained.

Fifth. Increasing the evaporating-surfaces by at least one-half over the ordinary train of open kettles (for each of the side kettles has an evaporating-surface of ninety square feet) without a proportionate increase in the number of kettles or in the area of the floor of the sugar-house occupied by my arrangement, while at the same time the flue-surface derived from my arrangement rivals the best plans known.

Sixth. Affording facilities for cleansing, inasmuch as both the fire and juice sides are accessible without removing a bolt, other than those which fasten the caps of the juice-channels of the flue-underlying portion of the long kettle.

Seventh. Requiring no more hands than now attend on an ordinary open train, although more than double the amount of surface has to be brushed, skimmed, and cleansed, it being obvious that by my arrangement a greater area of juice-surface is offered to the skimmer and brush, the sugar being thereby made clean, because what scum and impurities cannot be readily brushed into the troughs from the central kettles, owing to their violent boiling, is readily swept from the side divisions of the long kettle into the troughs, from the fact that the juice boiling up from the flue-underlying juice-space, the scum and impurities float toward the troughs. It will also be observed that I apply the heat at the battery end first, and the flues are so arranged that I can pass the heat first through the flue A, then return by the flues D and E, and then off by the flue K; but I can also use A and K as flues direct from the furnace, and D and E as return-flues to the chimney; or I can use A alone, or all the flues, A D E K, as direct flues leading to the chimney. Whatever variation in the direction of the draft of the flues D E K may be given, (as it can be if required, by suitable masonry or brick-work,) I always apply the heat directly from the furnace to the battery end of the train, because the striking point of sugar requires some 243° of heat, and the juice in the grandes may be received as low as 90°.

By the flue arrangement, as described, the heat of the furnace passes along the flue-surfaces of the kettles a distance of one hundred and eight feet, or as long as the heat can be economically applied.

Having thus fully, clearly, and exactly described the nature, object, and construction of my improvement in circulating boiler for

making sugar, &c., I claim as new and of my invention and desire to secure by Letters Patent—

1. The combination of the long kettle B C with the train of kettles L M N O R, the pipe S, the serpentine channel T U V, and the fire-flues A D E K, in the manner and for the purposes specified.

2. The combination of the troughs F, G, H, I, and J with the train of kettles L M N O R, and the long kettle B C, in the manner and for the purposes specified.

SAMUEL H. GILMAN.
